UNITED STATES PATENT OFFICE.

MALCOLM D. RIKER, OF DOVER, NEW JERSEY, ASSIGNOR TO MCKIERNAN-TERRY DRILL COMPANY, OF DOVER, NEW JERSEY, A CORPORATION OF NEW JERSEY.

LIFTING JACK.

Application filed October 28, 1921. Serial No. 511,089.

To all whom it may concern:

Be it known that I, MALCOLM D. RIKER, a citizen of the United States of America, and a resident of Dover, county of Morris, and State of New Jersey, have invented certain new and useful Improvements in Lifting Jacks, of which the following is a specification.

This invention relates to lifting jacks.

One of the objects of the invention is to provide for the efficient lubrication of the lifting members of a lifting jack.

Another object of the invention is to provide means in a lifting jack for maintaining the lifting power transmitting means or gearing in effective operative position and to prevent the separation of these elements.

Another object of the invention is to provide means for retaining lubricant in the casing head of a lifting jack thereby insuring the proper lubricant of the operating mechanism for the jack.

Further objects of the invention will appear from the following specification taken in connection with the drawings which form a part of this application and in which—

Fig. 1 is a sectional elevation of a lifting jack constructed in accordance with my invention, and

Fig. 2 is a perspective view of the cone collar which retains the lubricant in the casing head and retains the operating mechanism in operative position.

The lifting jack embodying my improvements may be briefly described as comprising a stationary member, a movable member or casing, lifting mechanism such as a screw and nut carried by the movable and stationary members, and operating means for the lifting members such as gearing. Means is provided for retaining the gearing in proper mesh and for retaining lubricant in the upper end or head of the movable member or casing. In the particular embodiment illustrated this means consists of a conical ring or collar which rests on a portion of the casing head and is adapted to engage a portion of the gearing.

Referring to the drawings there is shown a jack comprising a base 10, preferably of cast or forged metal and a stationary member or pedestal 11 secured to the base 10 as by welding indicated at 12. The pedestal 11 is preferably formed of commercial tubing and is provided with flat sides 13.

The movable member of the jack consists of a casing 14, preferably cylindrical, and this casing has secured thereto at its lower end lugs or inserts 15 having flat inner surfaces 16 positioned adjacent the flat sides 13 of the pedestal. These lugs therefore prevent rotation of the casing with respect to the pedestal as the casing is being raised.

The lifting mechanism comprises a nut 17 having a sleeve portion 18 conforming in shape to the bore or inner wall of the pedestal 11. The sleeve 18 is mounted in the upper end of the pedestal and the nut has formed thereon a laterally extending flange 19 which rests on the upper end of the pedestal 11.

Lifting screw 20 is threaded into the nut 17 and has secured thereto or formed integral therewith a worm gear 21 and an upwardly extending stud 22.

A casing head 23 is secured as by welding indicated at 24 to the upper end of the casing 14, the head having an inwardly extending annular flange 25 which rests on the upper end of the casing 14.

The worm gear 21 is positioned within the casing head and meshes with a worm 26 mounted on a stub shaft 27 carried by the casing head. Any suitable means for rotating the shaft may be used.

The head 28 is threaded into an opening at the upper end of the casing head 23 and a roller bearing 29 is positioned between the head 28 of the upper surface of the worm gear 21 and takes up the thrust during the operation of the jack. An opening 30 is formed in the casing head for the admission of lubricant and a threaded plug 31 closes the opening.

An oil conduit 32 in the stud 22 and in the screw 20 conducts oil to the contacting surfaces of the screw and nut.

In the operation of the jack constructed as above described it has been found that when the casing 14 is lowered the worm gear 21 tends to move relative to the worm 26 thereby moving these two parts out of proper mesh. In order to prevent this separation of the worm and worm gear a ring or collar 33, having in the present instance the shape of a truncated cone, is positioned between the lower face of the worm gear 21 and the flange 25 formed on the casing head. This collar insures the lowering of the casing head with the screw 20 and the worm 21.

gear 21 and also serves the additional function of retaining lubricant in the casing head thereby insuring the effective lubrication of the bearing and of the roller bearing 29.

Although one specific embodiment of the invention has been particularly shown and described, it will be understood that the invention is capable of modification and that 10 changes in the construction and in the arrangement of the various cooperating parts may be made without departing from the spirit or scope of the invention as expressed in the following claims.

15 What I claim is:

1. In a lifting jack, a pedestal, a casing movable thereon and including a casing head, a lifting screw, gearing in the head for rotating the screw and means located 20 between the gearing and casing head for retaining the gearing in operative position to rotate the screw and retain lubricant in the casing head.

2. In a lifting jack, a stationary member, 25 a movable member, a nut carried by the stationary member, a screw carried by the movable member, a gear in the movable member connected to the screw and means located between and engaging the gear and 30 a part of the movable member for retaining lubricant in the movable member in all positions of adjustment of said movable member.

3. In a jack, a pedestal, a casing movable 35 thereon and including a casing head, a nut carried by the pedestal, a screw carried by the casing engaging the nut, a gear in the casing head connected to the screw, means for rotating the gear and means located be-

tween and engaging the casing head and 40 gear for retaining lubricant in the head.

4. In a jack, a pedestal, a casing movable thereon, and including a casing head, a nut carried by the pedestal, a screw carried by the casing engaging the nut, a gear in the 45 casing head connected to the screw, means for rotating the gear and a conical collar located between and engaging the casing head and gear for retaining lubricant in the head.

5. In a jack, a pedestal, a casing movable 50 thereon, and including a casing head, a nut carried by the pedestal, a screw carried by the casing engaging the nut, a worm gear in the casing head connected to the screw, means including a worm for rotating the 55 gear and means located between the casing head and gear for retaining lubricant in the head and retaining the worm and worm gear in mesh.

6. In a jack, a pedestal, a casing movable 60 thereon and including a casing head, a nut carried by the pedestal, a screw carried by the casing engaging the nut, a gear in the casing head connected to the screw, means for rotating the gear and a collar having a 65 bearing in the casing head and engaging said gear.

7. In a jack, a pedestal, a casing movable thereon and including a casing head, a nut carried by the pedestal, a screw carried by 70 the casing engaging the nut, a gear in the casing head connected to the screw, means for rotating the gear and a collar mounted on an annular flange in said casing head and engaging the under surface of said gear. 75

In witness whereof, I have hereunto set my hand this 13 day of September, 1921.

MALCOLM D. RIKER.
